UNITED STATES PATENT OFFICE.

GUST W. PETERSON AND BERT T. WALLS, OF LONG BEACH, CALIFORNIA.

PENDANT ORNAMENT.

Application filed December 22, 1925. Serial No. 76,993.

The device of the present invention is in the nature of a pendant ornament adapted to be worn on a chain suspended around the neck, to be used as a watch fob, or to be used 5 as a pendant decoration for any purpose.

An object of the invention is to provide a pendant ornament of this character which may be unfolded and displayed in the form of a cross, or which may be folded into the 10 shape of a cube, and which, in either folded or unfolded position, will serve as an attractive ornament.

A further object of the invention is to provide a device of this character which will 15 be of extremely simple and practical construction, which will be neat and attractive in appearance, rugged and durable in use, which can be manufactured with comparative economy, and which includes means 20 for holding the same snugly and securely in folded position.

With the above noted and other objects in view, the invention consists in certain novel features of construction and combinations 25 and arrangements of parts, as will be more fully hereinafter set forth and pointed out in the claims. The invention may be more fully understood from the following description in connection with the accompanying 30 drawings, wherein

Fig. 1 is a perspective view of a device embodying the invention, showing the same in folded position.

Fig. 2 is a plan view of the device in completely opened position.

Fig. 3 is a transverse sectional view on the line 3—3 of Fig. 2.

Fig. 4 is a transverse sectional view on the line 4—4 of Fig. 1.

40 The device of the present invention preferably includes a plurality of hingedly connected sections, each of quadrilateral, pyramidal shape and so proportioned that when they are folded one upon the other, 45 they will form a cube.

In the drawings we have used the reference character 10 to designate the main or central section of the cross. Each side edge of the section 10 is connected by hinges 11 50 to similar sections 12, 13, 14 and 15 respectively. It will be noted that each section is of quadrilateral pyramidal form with the side faces thereof rising from the base at an angle of 45° so that the pyramids will 55 be exactly one half as high as they are wide. Hinged to the edge of section 15 by hinges

14² is a sixth section similar in shape to the sections above described.

By virtue of the shape and arrangement of the pyramidal sections, it will be evident 60 that they may be folded one upon the other to form a solid cube. In folding, the sections 12, 14 and 15 are first swung inwardly on their hinges until they engage the central section 10. Section 16 is then swung inwardly until it engages with the sections 65 12, 14² and 15. Section 13 carries means for locking the other sections against unfolding and is swung into position last. Secured to the rear flat face of the section 13 70 is a strap 17 terminating at its ends in spring fingers 18 adapted to overlie the edges of the sections 12 and 14, and retain the latter against unfolding movement. Integral with the strap 18 is an arm 19 disposed 75 at right angles to the strap and terminating at its end in a spring finger 20 adapted to overlie the flat face of the section 16. Preferably the finger 20 is formed with a depression 21 adapted to snap over a tip 22 80 on the rear face of the section 16.

The strap 18 may carry an eye 23 for the reception of a watch chain or any other appropriate type of flexible supporting device, 85 this eye serving as a hanger for the ornament regardless of whether the same is in folded or unfolded position.

Various changes and alterations might be made in the general form and arrangement of parts described, without departing from 90 the invention. Hence we do not wish to limit ourselves to the details set forth, but shall consider ourselves at liberty to make such changes and alterations as fairly fall 95 within the spirit and scope of the appended claims.

We claim:

1. A pendant ornament of the class described including six quadrilateral pyramidal sections, four of said sections being hingedly connected to the side edges of a fifth section, the sixth section being hingedly connected to the outer edge of one of the four sections above mentioned, said four sections being adapted for folding over into engagement with the fifth section, and the sixth section being adapted for folding over into engagement with the four sections, and means for locking all of said sections against unfolding including three spring fingers rigidly carried by the back of one of the four sections, said fingers snapping over two 100 105 110

others of said four sections and the sixth section.

2. A pendant ornament of the class described including a regular quadrilateral pyramidal section 10, of a height equal to one-half the length of an edge of its base, similar sections 12, 13, 14, 15 hingedly connected at their edges to the four side edges of section 10, another similar section 16 hingedly connected to the outer edge of section 15, all of said sections being foldable one upon the other to form a solid cube, and spring fingers rigidly carried by the section 13 for locking all of said sections against movement, said fingers including finfiers 18 embracing the sections 12 and 14, and a finger 20 engaging the section 16.
3. A pendant ornament of the class described including six quadrilateral pyrami-

dal sections, four of said sections being 20 hingedly connected to the side edges of a fifth section, the sixth section being hingedly connected to an outer edge of one of the four sections above mentioned, said four sections being adapted for folding over into 25 engagement with the fifth section, and the sixth section being adapted for folding over into engagement with the four sections, and means for locking all of said sections against unfolding, said means including a T-shaped 30 spring member rigidly secured to the back of one of said four sections, and right angularly disposed spring fingers at the three extremities of the T-shaped member adapted to snap over two others of said four sections 35 and the sixth section.
